PHYSIOTHERAPEUTIC DEVICE

Dale K. McMennamy, Van Nuys, Calif.

Application February 2, 1951, Serial No. 209,134

9 Claims. (Cl. 128—25)

1

This invention relates to a body and limb developer, and more particularly to a physiotherapeutic device for aiding paralytics to regain the power of self-locomotion.

An object of this invention is to provide a physiotherapeutic device which is particularly adapted to aid the paralytic in regaining the requisite muscular coordination and balance for normal locomotion.

Another object of this invention is to provide a therapeutic device which is particularly adapted to impart a walking-like motion to the legs of a paralytic to thereby aid the stricken paralytic in regaining the requisite muscular coordination for self-locomotion.

A further object of this invention is to provide a therapeutic device which is particularly adapted for use by paralytic children in regarding the power of self-locomotion, the device serving as a mobile vehicle during the period of physiotherapy.

A still further object of this invention is to provide a therapeutic device which can be readily adjusted to receive paralytic children in a relatively wide age group for the re-education of certain muscles.

A still further object of this invention is to provide a therapeutic device which can be selectively adjusted over the period of physiotherapy for supporting the paralytic in various attitudes from a seated position to a standing position, to thereby aid the paralytic in regaining the requisite balance for normal self-locomotion.

A still further object of this invention is to provide a physiotherapeutic device for paralytics which is relatively simple in structure and cheap to manufacture.

The above and still further objects and advantages of the present invention will become apparent upon consideration of the following detailed description of the invention when taken in conjunction with the accompanying drawings, wherein:

Figure 1 is a side elevational view of the therapeutic device of the present invention;

Figure 2 is a rear elevational view of the therapeutic device of the present invention, taken from the right of Figure 1;

Figure 3 is a bottom plan view of the therapeutic device of the present invention;

Figure 4 is an enlarged, fragmentary, sectional view taken along the line 4—4 of Figure 2;

Figure 5 is a fragmentary, perspective view of a two-throw crankshaft employed in the il-

2

lustrated embodiment of the physiotherapeutic device of the present invention;

Figure 6 is an enlarged, sectional view taken along the line 6—6 of Figure 3, with parts broken away and shown in section;

Figure 7 is an enlarged, fragmentary, sectional view taken along the line 7—7 of Figure 3; and

Figure 8 is an enlarged, fragmentary, detail view taken along the line 8—8 of Figure 1, with parts broken away and shown in section.

Referring now more particularly to the drawings, wherein like reference numerals have been used throughout the several views to designate like parts, there is shown the therapeutic device of the present invention, generally designated by the reference numeral 10, which includes a mobile base 11 adapted to be supported above a supporting surface 12. Rotatably journaled contiguous to the forward end of the base 11 is an upstanding steering post 13 which carries a steering column 14, the steering column being secured to the upper end of the steering post 13 by means of the spaced bolts 15, 16.

Underlying the forward end of the base 11 is a front wheel assembly 17 which is secure to the lower end of the steering post 13, the front wheel assembly embodying a horizontally disposed axle 18 having the wheels 19, 20 rotatably journaled contiguous to the free ends thereof.

Positioned contiguous to the rear end of the base 11 is a two-throw crankshaft 21 having a pair of double cranks thereon, which is mounted on the base 11 for rotary movement about a horizontally disposed, transversely extending axis. Disposed contiguous to and spaced outwardly of the sides of the base 11 are the rear wheels 22, 23 which are fixedly secured to the ends of the two-throw crankshaft 21. The front wheel assembly 17 including the wheels 19, 20 and the rear wheels 22, 23 cooperate to support the base 11 for movement along the supporting surface 12. Upon movement of the base along the supporting surface, the rear wheels 22, 23 drive the crankshaft 21.

Arranged in spaced, parallel relation with respect to the crankshaft 21 is a two-throw crankshaft 24 which is mounted contiguous to the forward end of the base 11 for rotary movement about a second horizontally disposed, transversely extending axis.

Extending longitudinally of the base 11 is a pedal 26 which is disposed between the crankshafts 21, 24 and has one end rotatably supported on the throw or double crank 28 of the crankshaft 21 and has the other end rotatably

supported on the opposed throw or double crank 29 of the crankshaft 24. Disposed in spaced, parallel relation with respect to the pedal 26 is a second pedal 27 which has one end rotatably journaled on the throw 30 of the crankshaft 24 and has the other end rotatably journaled on the opposed throw 31 of the crankshaft 24. Accordingly, upon imparting a rotary movement to the crankshaft 24, the assembly of the crankshafts and the pedals 26, 27 will be actuated to impart a walking-like motion to the legs of a paralytic when the legs are secured to the pedals.

Secured to the mobile base 11 is a frame 32 which includes the spaced, inverted, upstanding, U-shaped frame members 33, 34 which are secured on opposite sides of the base 11.

Carried by the frame 32 is a support 35 which is adapted to engage rear portions of the paralytic. The support 35 embodies a horizontally disposed, U-shaped bracket 36 which has its legs secured to the adjacent frames 33, 34 by means of the slide blocks 37. The sliding blocks 37 are provided with suitable hand actuatable means 38 for engagement with the frame 32 to thereby hold the support 35 in a select position of its movement toward and away from the base 11, the support being slidably mounted on the frame 32. The support further includes spaced, upstanding side plates 39, 40, the side plate 39 being secured to the adjacent leg of the U-shaped bracket 36 and slidably supported on the adjacent leg of the frame section 33 of the frame 32. The side plate 40 is similarly secured to the adjacent leg of the horizontally disposed, U-shaped bracket 36 and is slidably supported on the adjacent leg of the frame section 34 of the upstanding frame 32. Disposed between the side plates 39, 40 is a seat section 41 which is pivotally mounted contiguous to one end by means of the bolts 42 for movement from the horizontal position to various inclined positions with respect to the horizontal. Arranged contiguous to the upper end of the seat section 41 is a back section 43 which has one end pivotally connected to the other end of the seat section 41 by means of the hinge 44. Connected between the back section 43 and the adjacent side plate are connecting links 45 which mount the back section 43 for movement from a vertical position to various inclined positions with respect to the vertical in response to the movement of the seat section 41 from the horizontal position to various inclined positions with respect to the horizontal. Accordingly, the support 35 can be selectively adjusted over the period of physiotherapy for supporting the paralytic in various attitudes from the seated position illustrated by the full lines in Figure 6 to the standing position illustrated by the broken lines in Figure 6, to thereby aid the paralytic in regaining the requisite balance for normal self-locomotion.

Suitable means are carried by the seat section and engage the side plates 39, 40 for detachably securing the seat in a select position of its movement. The means for securing the seat section in select positions of its movement includes the barrels 46, 47 carried on the under surface of the seat section 41, the barrels supporting the spring-biased plungers 48, 49 which are selectively engageable in apertures 50 provided on the side plates 39, 40. As clearly shown in Figure 1, the apertures 50 are disposed along the circumferential arc of a circle having the pivot 42 as a center.

Resting upon the pedals 26, 27 are the foot

rests 52, 53 which are adapted to secure the feet of a paralytic to the adjacent one of the pedals. Suitable means are operatively connected to each of the foot rests and the adjacent one of the pedals for holding the foot rests at a select position along the adjacent one of the pedals and at a select inclination with respect to the latter. Since the mounting structure for each of the foot rests 52, 53 is the same, it will suffice to describe only one in detail. In Figure 7, there is shown the foot rest 53 which is supported on the pedal 27 by means of the spaced, U-shaped brackets 54, 55. Extending through the bottom 56 of the foot rest 53 is a set screw 57 which extends through the bight of the bracket 55 and engages the pedal 27. Extending between the legs of the bracket 54 is a pin 58 which is adapted to underlie and bear against the pedal 27. Upon movement of the threaded set screw 57 into engagement with the pedal 27, the adjacent end of the foot rest 53 can be fixedly positioned with respect to the pedal 27. A second set screw 59 extends through the floor 56 of the foot rest 53 and through the bight of the bracket 54 and engages the pedal 27. The legs of the bracket 54 are provided with opposed pairs of spaced apertures 60 for selectively supporting a pin 61 at select positions along the legs of the bracket 54. Upon urging the free end of the set screw 57 into engagement with the pedal 27, the front end of the foot rest 53 can be elevated above the pedal 27 to a height predetermined by the supported position of the pin 61. When the pin 61 engages the under surface of the pedal 27, the maximum elevation of the foot rest has been attained until the pin is supported in a different pair of the spaced apertures 60. Each of the foot rests 52, 53 is provided with a cup 63 engageable over the toe of the shoe of the adjacent foot of the paralytic, which, in cooperation with straps, not shown, effect the securement of the adjacent foot to the adjacent foot rest.

Since the support 35 can be adjusted with respect to the base 11, the therapeutic device can be adjusted to accommodate children and adults in a relatively wide age and size group. As clearly shown in Figure 4, the support is provided with a pair of spring-biased plungers 65 which are selectively engageable in spaced apertures 66 provided in the adjacent legs 67 of the adjacent U-shaped frames of the upstanding frame structure 32. The plungers 65 are mounted within cylindrical housings 68 for sliding movement longitudinally thereof and transversely of the legs 67 of the frame 32. Disposed within the respective housings 68 are springs 69 which are circumposed about the respective plungers 65 and normally bias the latter to the position illustrated in Figure 4. Upon applying an outwardly directed force to each plunger 65, the end thereof normally disposed within leg 67 can be disengaged therefrom to permit the support 35 to be adjusted with respect to foot rests 52 and 53.

Spaced above the base 11 is a handle structure 70 which extends longitudinally of the base and is pivotally supported on the steering column 14 by means of the bolt 71 for swinging movement in a vertical plane about a horizontal axis. Suitable means are operatively connected between the handle structure 70 and the steering column 14 for holding the handle structure 70 in select positions of its rocking movement. As clearly shown in Figure 6, a collar 72 is slidably supported on the steering column 14, the collar being secured in select positions of its movement along

the column 14 by means of the hand actuatable set screw 73 which is supported in threaded engagement with the collar and selectively engageable with the column 14. Interconnected between the collar or sleeve 72 is a linkage 73' which has one end pivotally connected to the collar 72 and has the other end pivotally connected to the handle structure 70.

The handle structure 70 includes a base 75 which is pivotally secured to the steering column 14 by means of the bolt 71, the base including an abutment 76 spaced from the pivot 71. Disposed longitudinally of the base 75 is a hand grip 77 which is mounted for extensible and retractile movement with respect to the base toward and away from the adjacent support 35. The hand grip 77 carries a stop element 78 provided with a set screw 79 engageable with the adjacent portions of the base 75 to hold the hand grip 77 in select positions of its extensible or retractile movements. The movable stop 78 abuts against the fixed stop 76 of the base 75 to limit the extensible movement of the hand grip 77. The select position of the hand grip 77 with respect to the base is selected according to the size and position of the paralytic operating the device of the present invention.

In actual use, the paralytic is placed within the upstanding frame structure 32 and supported on the support 35 in a position predetermined by the length of therapy and the paralytic's capabilities. The legs of the paralytic are then secured to the foot rests 52 and 53 in the manner previously described and the device is moved along the supporting surface 12 by the paralytic actuating the pedals 26 and 27, or by an individual who can grasp the rearwardly disposed bight of the horizontally disposed bracket 36 to effect the movement of the mobile base 11.

Considering the operation of the parts of the device in greater detail, it is to be noted that the construction is such that each crank of a crankshaft is aligned, longitudinally of the base, with a crank of the other crankshaft (Figure 3). Further, since the two cranks of a crankshaft are oppositely disposed on said crankshaft, one pedal 26 will be moving rearwardly while the other pedal 27 will be moving forwardly, in a motion particularly adapted to simulate closely the movements of the feet of a person when the person is walking. Further, it is to be noticed that the operation of the seat section 41 is such that when said seat section is swung upwardly, more and more of the weight of the paralytic is placed upon the pedals, responsive to progressively increased upward adjustments of the seat section. Thus, as the paralytic progresses during continued and repeated treatments, he or she is enabled to gradually impose an ever-increasing weight on the feet and lower limbs. At the same time, the muscles used during normal walking are exercised. This is the operation of the basic parts of the structure, and this operation is aided by the adjustability of the seat section longitudinally of the legs 67 of the upstanding frame 32, the up and down adjustments of the handle structure, the tiltable adjustment of the foot rests detailed in Figure 7, and the hand grip mounted for extensible and retractile movement toward and away from the support 35.

Although only one embodiment of the therapeutic device of the present invention has been described, it is readily apparent that numerous modifications can be made without departing

from the spirit of the invention as set forth in the appended claims.

What I claim is:

1. A therapeutic device for paralytics comprising a mobile base, a pair of longitudinally spaced transversely extending two-throw crankshafts rotatably journaled in said base and actuatable in response to the movement of said mobile base, a first pedal extending longitudinally of said base intermediate said pair of crankshafts and having one end connected to one throw of one of said crankshafts and having the other end connected to the opposite throw of the other of said crankshafts, a second pedal spaced from said first pedal and having one end connected to the other throw of said one shaft and having the other end connected to the other throw of said other shaft, a frame carried by said mobile base, a support adapted to engage the rear portions of a paralytic positioned within said frame and mounted therein for movement toward and away from said base, means carried by said support and engaging said frame for detachably securing said support in a select position of its movement with respect to said base.

2. A therapeutic device for paralytics comprising a mobile base, a pair of longitudinally spaced transversely extending two-throw crankshafts rotatably journaled in said base and actuatable in response to the movement of said mobile base, a first pedal extending longitudinally of said base intermediate said pair of crankshafts and having one end connected to one throw of one of said crankshafts and having the other end connected to the opposite throw of the other of said crankshafts, a second pedal spaced from said first pedal and having one end connected to the other throw of said one shaft and having the other end connected to the other throw of said other shaft, a frame carried by said mobile base, a support carried by said frame adapted to engage the rear portions of a paralytic, and a foot rest carried by each of said pedals and adapted to be secured to the adjacent foot of the paralytic, said support including spaced upstanding side plates carried by said frame, a seat section mounted contiguous to one end on said side plates for pivotal movement from a horizontal position to various inclined positions with respect to the horizontal, a back section having one end pivotally connected to the other end of said section, and linkage means connected between said side plates and said back section for mounting the latter for movement from a vertical position to various inclined positions with respect to the vertical in response to the movement of said seat section from said horizontal position to the various inclined positions with respect to the horizontal, and means carried by said seat section and engaging one of said side plates for holding said seat section in a select position of its pivotal movement.

3. A therapeutic device for paralytics comprising a base adapted to be supported above a supporting surface, an upstanding steering post rotatably journaled contiguous to one end of said base, a front wheel assembly underlying said one end of said base and secured to the lower end of said steering post, a first two-throw crankshaft positioned contiguous to the other end of said base and mounted on the latter for rotary movement about a first horizontally disposed transversely extending axis, a rear wheel secured to each end of said first crankshaft, said front wheel assembly and said rear wheels cooperating

to support said base for movement along said supporting surface, a second double-throw crank-shaft arranged in spaced parallel relation with respect to said first crankshaft and mounted contiguous to said one end of said base for rotary movement about a second horizontally disposed transversely extending axis, a pedal operatively connected between each pair of opposed throws of said crankshafts, a frame carried by said mobile base, a support carried by said frame adapted to engage the rear portions of a paralytic, a foot rest carried by each of said pedals and adapted to secure the feet of a paralytic to the adjacent one of said pedals, a handle structure spaced above and extending longitudinally of said base and pivotally supported on said steering post for swinging movement in a vertical plane, and means operatively connected between said handle structure and said steering post for holding said handle structure in select positions of its pivotal movement.

4. A therapeutic device for paralytics comprising a base adapted to be supported above a supporting surface, an upstanding steering post rotatably journaled contiguous to one end of said base, a front wheel assembly underlying said one end of said base and secured to the lower end of said steering post, a first two-throw crankshaft positioned contiguous to the other end of said base and mounted on the latter for rotary movement about a first horizontally disposed transversely extending axis, a rear wheel secured to each end of said first crankshaft, said front wheel assembly and said rear wheels cooperating to support said base for movement along said supporting surface, a second double-throw crank-shaft arranged in spaced parallel relation with respect to said first crankshaft and mounted contiguous to said one end of said base for rotary movement about a second horizontally disposed transversely extending axis, a pedal operatively connected between each pair of opposed throws of said crankshafts, a frame carried by said mobile base, a support carried by said frame adapted to engage the rear portions of a paralytic, a foot rest carried by each of said pedals and adapted to secure the feet of the paralytic to the adjacent one of said pedals, a handle structure spaced above and extending longitudinally of said base and pivotally supported on said steering post for swinging movement in a vertical plane, and means operatively connected between said handle structure and said steering post for holding said handle structure in select positions of its pivotal movement, said handle structure including a hand grip mounted for extensible movement toward said other end of said base and into a position contiguous to said support, and means for holding said hand grip in select positions of its extensible movement.

5. A therapeutic device for paralytics comprising a mobile base, a pair of longitudinally spaced transversely extending two-throw crankshafts rotatably journaled in said base and actuatable in response to the movement of said mobile base, a first pedal extending longitudinally of said base intermediate said pair of crankshafts and having one end connected to one throw of one of said crankshafts and having the other end connected to the opposite throw of the other of said crankshafts, a second pedal spaced from said first pedal and having one end connected to the other throw of said one shaft and having the other end connected to the other throw of said other shaft, a frame carried by said mobile base, a sup-

port carried by said frame adapted to engage the rear portions of a paralytic, a foot rest carried by each of said pedals and adapted to be secured to the adjacent foot of the paralytic, and means operatively connected to each of said foot rests and the adjacent one of said pedals for holding each of said foot rests in a select position along the adjacent one of said pedals and at a select inclination with respect to said adjacent one of said pedals.

6. A therapeutic device for paralytics comprising a base, pairs of front and rear wheels supporting said base for movement over a supporting surface, front and rear two-throw crankshafts journaled in and spaced longitudinally of said base, at least one of said crankshafts being fixed to one of the pairs of wheels to rotate jointly therewith, the respective throws of one crank-shaft being aligned longitudinally of the base with the respective throws of the other crank-shaft, a pair of generally horizontal pedals extending longitudinally of the base, said pedals being respectively connected at their opposite ends to the aligned throws of the respective 15 crankshafts to link the crankshafts for joint rotation, said pedals having reciprocating movement longitudinally of the base responsive to joint rotation of the crankshafts, a seat section mounted upon said base above and rearwardly from the pedals and adapted to support the rear portions of a paralytic, and foot rests adapted to support the feet of a paralytic, said foot rests overlying the pedals and being mounted thereon for adjustment independently of one another relative to the pedals 20 25 30 35 supporting the same, to dispose the feet of a paralytic supported by said seat section in selected positions relative to the pedals.

7. A therapeutic device for paralytics comprising a base, a pair of front and a pair of rear wheels supporting said base for movement over a supporting surface, front and rear two-throw crankshafts journaled in and spaced longitudinally of said base, one of the crankshafts being fixed to one of the pairs of wheels to rotate jointly therewith, the respective throws of one crank-shaft being aligned longitudinally of the base with the respective throws of the other crank-shaft, a pair of generally horizontal pedals extending longitudinally of the base, said pedals being respectively connected at their opposite ends to the aligned throws of the respective crankshafts to link the crankshafts for joint rotation, said pedals having reciprocating movement longitudinally of the base responsive to joint rotation of the crankshafts, a seat section mounted upon said base above and rearwardly from the pedals and adapted to support the rear portions of a paralytic, and foot rests adapted to support the feet of a paralytic, said foot rests overlying the pedals and being mounted thereon for independent adjustment vertically of the pedals to selected elevations and angular relationships relative to the pedals supporting the same, to dispose the feet of a paralytic supported by said seat section in selected positions relative to the pedals and seat section.

8. A therapeutic device for paralytics comprising a base, a pair of front and a pair of rear wheels supporting said base for movement over a supporting surface, front and rear two-throw crankshafts journaled in and spaced longitudinally of said base, one of the crankshafts being fixed to one of the pairs of wheels to rotate jointly therewith, the respective throws of one crank-shaft being aligned longitudinally of the base

with the respective throws of the other crank-shaft, a pair of generally horizontal pedals extending longitudinally of the base, said pedals being respectively connected at their opposite ends to the aligned throws of the respective crankshafts to link the crankshafts for joint rotation, said pedals having reciprocating movement longitudinally of the base responsive to joint rotation of the crankshafts, an upstanding frame rigid with and extending upwardly from the base, a seat section mounted upon said frame above and rearwardly from the pedals and adapted to support the rear portions of a paralytic, said seat section having one edge pivotally connected to the frame for swinging movement of the seat section to selected positions inclined from the horizontal, means for holding the seat section against movement from each of said inclined positions, means for adjusting the seat section bodily toward and away from said base, and foot rests adapted to support the feet of a paralytic, said foot rests overlying the pedals and being mounted thereon for independent adjustment vertically of the pedals to selected elevations and angular relationships relative to the 25 pedals supporting the same, to dispose the feet of a paralytic supported by said seat section in selected positions relative to the pedals and seat section.

9. A therapeutic device for paralytics comprising a base, a pair of front and a pair of rear wheels supporting said base for movement over a supporting surface, front and rear two-throw crankshafts journaled in and spaced longitudinally of said base, one of the crankshafts being 30 fixed to one of the pairs of wheels to rotate jointly therewith, the respective throws of one crank-shaft being aligned longitudinally of the base with the respective throws of the other crank-shaft, a pair of generally horizontal pedals extending longitudinally of the base, said pedals being respectively connected at their opposite ends to the aligned throws of the respective

30

35

40

crankshafts to link the crankshafts for joint rotation, said pedals having reciprocating movement longitudinally of the base along generally horizontal lines responsive to joint rotation of the crankshafts, a frame rigid with and upstanding from the base, a support for the rear portions of a paralytic mounted upon the frame above and rearwardly from the pedals and including a pair of side plates connected to the frame for vertical adjustment toward and away from the base, said support further including a seat section extending between the plates and having its front edge pivotally connected to the plates for swinging adjustment of the seat section to selected positions inclined from the horizontal, said swinging adjustment of the seat section constituting means effective for selectively varying the portion of a paralytic's weight carried by the pedals as compared to the portion of said weight carried by the seat section, and foot rests adapted to support the feet of the paralytic, said foot rests overlying the pedals and respectively having their front and rear ends mounted upon their associated pedals for independent adjustment vertically of the pedals to provide means for adjusting the foot rests to selected elevations and angular relationships relative to the seat section and to the pedals.
